[57] CLAIM

The ornamental design for an electronic metronome,
substantially as shown and described.

DESCRIPTION

FIG. 1 is a front elevational view of an electronic metronome showing my new design;
FIG. 2 is a rear elevational view thereof;
FIG. 3 is a top plan view thereof;
FIG. 4 is a bottom plan view thereof;
FIG. 5 is a right side elevational view thereof, the left
side being a mirror image thereto;
FIG. 6 is a cross-sectional view thereof taken generally
along the line 6—6 of FIG. 1 with the inner contents
thereof omitted for clarity.
